COUNTING DEVICE FOR OVERVOLTAGE

Paul Fehr, Zug, Switzerland, assignor to Landis
& Gyr A. G., a body corporate of Switzerland

Application August 5, 1943, Serial No. 497,441
In Switzerland November 7, 1942

3 Claims. (Cl. 235—92)

1

There are several devices known in the art for counting voltage surges on long overhead lines due to atmospheric influences or switchings. Such devices are based on magnetic, dynamic, thermal or chemical action of the current deflected by the protective devices in use.

For instance, in a known form of embodiment, at a voltage-dependent resistance of the over-voltage conductor, a part of the voltage drop caused by the deflected (or discharged) current is tapped and conveyed to the two coatings of a condenser to which an electro-magnetically operated counting train is placed in parallel. After having been charged, the condenser discharges itself over the counting train and moves the same forward by one step.

Another known type utilizes the thermal action of the deflected current by passing an endless strip of paper longitudinally and transversely between a spark gap, whereby the strip gets punctured at the incidence of a voltage surge.

In addition other arrangements have been known, which utilize electro-magnets in connection with spark gaps, explosion spark gaps, coherers, &c.

The purpose of all these known devices is to provide a check of the behaviour of the overvoltage conductor during the service and, for instance, to ascertain how often the excess voltage conductor is affected during a thunderstorm and thus protects the plant from damage; in which part of the overhead line the lightning conductors have acted and, if possible, to measure the approximate strength of the discharged current.

Counting of voltage surges makes considerable demands on the counting devices, in view of the fact that the by-passed currents have a very short duration, i. e. 10^{-6} to 10^{-2} sec. and have a peak value of the order of 1000 amperes.

The present invention for counting momentary current impulses is characterized by the fact that a fraction of the deflected currents flowing through the conductance resistance is conveyed over a resistance which is in a tank filled with gas, whereby the gas expands under the influence of the ensuing heating and actuates the counting device through the medium of a flexible diaphragm.

The fundamental principle of the inventive idea may appear from a given form of embodiment according to the accompanying drawing, in which

Fig. 1 shows a diagram of the arrangement.

Fig. 2 is a cross-section of the gas-filled counting tank and

2

Figs. 3 and 4 illustrate other forms of embodiment.

The invention is based on the utilization of the thermal action of the deflected current, whereby this—according to the diagrammatic representation in Fig. 1—is conveyed over a filament resistance 1, which is in the counting tank 2 filled with gas. The closure of the tank 2 forms a flexible metallic diaphragm 3 being in connection with a counting train 4. Between the overhead line 5 and the ground lies the protective conductor 6. The counting device is interposed between protective conductor 6 and grounded conductor 7, whereby the deflected current passes via the parallel connection of a voltage-dependent resistance 8 and a reactor (or choking coil) 9. The counting train 4 and the metallic diaphragm 3 are mechanically interconnected.

Fig. 2 represents a sectional view of a form of embodiment of the actuating device for the counting train. The numeral 3 designates a diaphragm consisting of a corrugated metallic tube or pipe being slightly extensible in axial direction. The tube piece with flange 10 serves as connection between the corrugated metallic tube and the glass foot sealed onto it. The tank thus formed accommodates inside a filament resistance 1 carried by supports 12 that are adapted as current leads. The hollow space is filled with an inert gas possessing a small specific heat value. A socket 13 with connecting plug 14 holds the whole arrangement together.

On the lid of the corrugated metallic tube 3 a pin 15 is provided which transfers the movement of the diaphragm via the lever 16 by means of toothed segment 17 and gear wheel 18 onto the counting train 19.

In axially opposite position there is a compensating diaphragm 20 with which the influences of the ambient temperature on the diaphragm are nullified.

The action of the aforementioned device is as follows:

If a discharge occurs in conductor 6, the deflected current produces at the voltage-dependent resistance 8 a voltage drop. This voltage drop results in the transfer of a fraction of the deflected current over the filament resistance 1, heating it. The heat thus produced is given off to the gas in the counting tank, which gas expands in consequence of its warming and drives the diaphragm 3 forwards, so that the pin 15 presses against the lever 16 which—by means of the toothed segment 17—turns the gear wheel 18 and hence the counting train 19.

Resistance 8 preferably is of the type whose value is an inverse function of the current passing through. Thus, as the current due to a surge rises in intensity, the drop across resistance 8 may rise somewhat with the current and thereafter remains at a predetermined maximum value. Since the filament resistance is connected directly across resistance 8, it is clear that the limit of maximum voltage drop across resistance 8 serves to protect the filament resistance against excessive currents being forced through it. Thus, resistance 8 has a tendency to smooth or flatten the voltage rise across it as current goes up and preserves filament resistance 1 from destruction in case of intense discharge.

The reactor 9 connected in parallel to the voltage-dependent resistance 8 has in turn for its task to withhold from the counting tank the succeeding current emanating from the line voltage, which current flows after the proper rush discharge. This is achieved by selecting such a value for the inductance of the reactor 9 that its impedance for the rush discharge is very high. A comparatively small inductance is required for this purpose due to the steep current surge. Such a small inductance, however, offers a low impedance for the succeeding current after the initial steep wave front has passed. Such deviation of the succeeding current is necessary because its I^2Rt -value may assume very high figures, and this would lead to the destruction of the filament resistance.

The device may likewise be so disposed that the pin 15 of the diaphragm 3 directly controls a contact 21 (Fig. 3) which operates a relay 22, thus actuating the counting train 4. It is further conceivable that the counting train be driven by a clockwork 23 (see Fig. 4) and that the axial shifting of the pin 15 causes the clockwork to run down or arrests it by releasing the disk 25 for one revolution at a time. This, for instance, is brought about so, that the pin 15 in its rest position impedes the disk 25 from rotating because it is in the path of an arresting pin 26. If the pin 15

moves upwards, the disk is set free and performs an almost complete revolution, that is until an arresting stud 27 engages the pin 15. By this rotation the counting train has meanwhile been driven through one figure only.

When the gas in the counting tank 2 cools off, the pin 15 moves downwards thereby releasing the arresting stud 27; the disk 25 continues to rotate until the arresting stud 26 again impinges on pin 15 and the original position is again restored.

The aforescribed arrangement is adapted in its employment for the counting and in combination with a suitable recording device for determining the approximate strength of the deflected current, whereby the expansion of the diaphragm is utilized as a base value.

It will be evident that equivalents of the parts of the arrangement employed to accomplish the action of my said device might readily be devised which, however, would not depart from the scope of my invention.

Having now particularly described and ascertained the nature of my present invention and in what manner the same is to be performed, I declare that what I claim is:

1. A device for counting momentary power surges such as caused by lightning on a transmission line, said device including a main current conducting path, a resistance shunted across said main current conducting path, a gas-filled expandable chamber surrounding said resistance with the gas being heated by said resistance, a counting device associated with said expandable chamber to be operated by each expansion cycle.

2. The system of claim 1 whereby said main current conducting path comprises an inductance.

3. The system of claim 1 wherein said main current conducting path has a resistance characteristic such that the voltage drop across said path tends toward a maximum value irrespective of increase in current whereby said resistance shunted across said path is protected against excessive voltages.

PAUL FEHR.
